CLAIM

The ornamental design for a belt mount rifle sling holder, as shown and described.

DESCRIPTION

FIG. 1 is a perspective back left view of the sling holder in accordance with the invention;

FIG. 2 is a perspective front left view thereof;

FIG. 3 is a back view thereof;

FIG. 4 is a front view thereof;

FIG. 5 is a top side view thereof;

FIG. 6 is a bottom view thereof;

FIG. 7 is a right view thereof; and,

FIG. 8 is a left view thereof.

The surface indicia of parallel contour lines do not depict surface ornamentation.
